SEED PLANTER SHOE FOR OPENING A FURROW

Donald E. Williams, Garden City, Kans., assignor to
Aera-Plant, Inc., Newton, Kans., a corporation of
Kansas

Filed Mar. 30, 1964, Ser. No. 79,251

Term of patent 14 years

(Cl. D35—2)

FIG. 1 is a side elevational view of a seed planter shoe for opening a furrow, showing my new design;

FIG. 2 is a front elevational view thereof;

FIG. 3 is a rear elevational view thereof;

FIG. 4 is a top plan view thereof;

FIG. 5 is a bottom plan view thereof; and

FIG. 6 is a cross sectional view taken on line 6—6 of FIG. 2.

I claim:

The ornamental design for a seed planter shoe for opening a furrow, as shown.
